UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

STEREOTYPE-PLATE-FINISHING MACHINE.

1,212,049.

Specification of Letters Patent.

Patented Jan. 9, 1917.

Application filed January 30, 1911. Serial No. 605,573.

To all whom it may concern:

Be it known that I, SAMUEL G. Goss, a citizen of the United States, residing at Glencoe, in the county of Cook and State 5 of Illinois, have invented certain new and useful Improvements Relating to Stereotype-Plate-Finishing Machines, of which the following is a specification, reference being had to the accompanying drawings.

10 This invention relates to stereotype plate finishing machines and has for one of its objects to provide a construction in which the forward path of the plate is on a decline so that at appropriate times the plate will 15 by gravity slide through the machine to have the various operations performed upon it.

Another object is to provide a carriage which shall receive the finished plate in an inclined position and deliver it to a carrier in vertical position, the carrier being 20 adapted to accommodate a plurality of stereotype plates at one time.

Another object of my invention is to improve stereotype plate finishing machines in 25 sundry details hereinafter pointed out.

The means by which I have accomplished these ends are shown in the accompanying drawings and hereinafter specifically described.

30 That which I believe to be new will be set forth in the claims.

In the drawings:—Figure 1 is a side elevation of my improved machine; Fig. 2 is a front end view of the plate trimming machine proper, looking at it diagonally downward from the right in Fig. 1; Fig. 3 is a section taken on line 3—3 of Fig. 4 with the carriage shown in inclined position resting upon an appropriate support instead of in 35 vertical position as in Fig. 4; Fig. 4 is a top plan view of the carriage and its operating and coating mechanism; Fig. 5 is a section on line 5—5 of Fig. 6; Fig. 6 is a central sectional view of the parts shown in the 40 left hand end of Fig. 3, but with the carriage shown in vertical position; Fig. 7 is an enlarged detail, being a section on line 7—7 of Fig. 2; Fig. 8 is an enlarged detail, being a diagrammatic view showing the 45 difference in shape between the two cam grooves hereinafter described; Fig. 9 is an 50 enlarged detail, being a view of the arm which operates the stops which hold the plate in position upon the carriage; and Fig.

10 is an enlarged detail, being a section on line 10—10 of Fig. 2.

Referring to the several figures of the drawings:—20 indicates a drum rotatably mounted in bearing-rings 21—22, suitably supported by the framework 23. 24 indicates a worm-gear mounted on the outside of said drum, meshing with which is a worm 25 non-rotatably mounted upon a sleeve 25^a which is loosely mounted upon a drive-shaft 26 suitably journaled in the framework and 60 provided with a drive-pulley 27 adapted to be driven from any suitable source of power.

28 indicates a bevel-gear keyed upon the shaft 26. 29 indicates a bevel-gear meshing with said gear 28, said gear 29 being non-rotatably mounted upon the rear end of a countershaft 30 that is suitably mounted in 70 said framework. 31 indicates a pulley mounted upon the front end of said shaft 30, and 32 indicates a pulley upon the front 75 end of another countershaft 33 mounted in suitable bearings in said framework. 34 indicates a rotary cutter mounted upon the rear end of said counter-shaft 33. 35 indicates a belt connecting said pulleys 31 and 80 32 to cause them to rotate together.

36 indicates one of the members of a clutch keyed upon the sleeve 25^a and 37 indicates the coacting clutch member feathered upon the shaft 26. 85

38 indicates a shifting yoke of the ordinary type formed integral with a collar 39 which is journaled by means of a pin 40 upon the lower end of a bracket 41 depending from a suitable portion of the frame- 90 work.

42 indicates an arm depending from the collar 39, to the lower end of which is pivotally connected one end of a link 43, the other end of which link is pivotally connected to the upper end of an arm 44 non-rotatably secured to a shaft 45 which is mounted in suitable brackets 46 in the framework. 95

47 indicates a lever non-rotatably secured upon the shaft 45, provided with a suitable handle 48. 49 indicates a coiled spring connected to said lever and to the framework above the lever tending at all times to hold the lever in its raised position. 100

50 indicates an arm non-rotatably secured upon the shaft 45, to the lower end of which a link 51 is pivotally secured. The upper 105

end of the link 51 is pivotally secured to one arm of a bell-crank lever 52 which is journaled upon the upper end of a bracket 53.

54 indicates a bell-crank lever journaled upon the outer end of a bracket 55, the lower arm of the lever 54 extending alongside of the inwardly-extending arm of the lever 52. 56 indicates a plate secured to the side of said inwardly-extending arm of the lever 52, with the face of which plate the lower end of the lever 54 engages when the lever 52 is turned clockwise as shown in Fig. 2, when it prevents the return of the lever 52 in a counter-clockwise direction, as will be 10 15 readily understood.

57 indicates a roller journaled on the upper end of the lever 54, and 58 indicates a cam lug on the periphery of the drum 20 adapted to engage said roller 57 once in 20 each rotation of the drum, as hereinafter described.

59 indicates short shafts one of which is journaled upon each side of the drum 20, provided with inwardly-projecting arms 60 mounted on sleeves 61 thereon. On each shaft 59 is mounted an arm 62 provided with a roller 63 adapted to run on a cam ring 64. 65 indicates longitudinally-extending ribs movable up and down on the inner periphery of the drum 20 and resting on the inner ends of said arms 60. When the drum 20 is rotated out of the position shown in Figs. 1 and 2, the rollers 63 are drawn inward by the cams 64, thus raising the ribs 65 relative to the drum, exactly as shown and described in my application Ser. No. 519,387, filed September 24, 1909.

66—67 indicate standards rising diagonally from the frame and supporting a heavy rod 68, upon which is mounted, extending longitudinally thereof within the drum, the shaving knife 69.

Extending transversely from each side of the standard 66 is a trunnion 69, upon which 45 trunnions is pivotally mounted a table 70. 71 indicates a stereotype plate just as it comes from the casting box in position on the table 70. As shown in Figs. 1 and 2, the table 70 is made up of three portions, being 50 semi-cylindrical at one end to fit the curvature of the plate 71, the other end of the table being also semi-cylindrical but of a smaller diameter and provided with transversely-extending flanges, the two semi-cylindrical portions being joined by an intermediate conical portion. As shown in Fig. 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 contact with the knife 69 which shaves the inner peripheries of the ribs 76 which extend circumferentially around the interior of the plate, thus giving the plate the precise thickness necessary for proper work in the press. At about the time that the plate completely passes the shaving knife 69, the roller 57 rides up the cam 58, moving the lower arm of the lever 54 to the right in Fig. 2, permitting the horizontally-extending arm of the lever 52 to be raised by the action of the spring 49 which forces the lever 47 upward, throwing the clutch member 37 out of engagement with the clutch member 36 and permitting the drum to stop. The drum will stop very quickly since it is rotated very slowly and its momentum is very small, stopping always with the ribs 65 substantially in alignment with the transversely-extending flanges of the table 70. As the drum assumes its original normal position, the rollers 63 are forced outward by the weight of the plate 71 upon the ribs 65, being permitted to move outward by the appropriately-located openings in the cam rings 64. Thereupon the plate 71 slides out of the drum by gravity, there being now no means for preventing the movement of the plate, since the lug 74 which contacted the stop 75 was on the tail 77 of the plate which was cut off by the rotary cutter. Coming now to the mechanism for receiving the plate from the drum, cooling the plate, and delivering it standing on end, 77 indicates standards rising from the frame 23, in the upper ends of which is journaled a shaft 78. Keyed upon said shaft 78 are two collars 79-80, rising from each of which is an arm 81, to the upper ends of which arms is fixedly secured a carriage 82 substantially in the form of a semi-cylinder of a curvature adapted to fit a stereotype plate. 83 indicates an arm depending from the collar 79, to the lower end of which is pivotally secured a link 84, the forward end of which is pivotally secured to the upper end of an arm 85 loosely mounted on a shaft or spindle 86 extending across the machine. 87 indicates a link pivoted at its rear end to the arm 85 intermediate of its ends, and connected at its front end to a closed yoke 88 which embraces loosely a shaft 89 extending across the machine and journaled in standards 90. 91 indicates a cam disk provided with an annular cam groove 92 in which works a stud or roller 93, as hereinafter described, said stud or roller 93 being carried by said yoke 88. 94 indicates a bevel gear keyed upon the shaft 89, meshing with which is a bevel gear 95 keyed upon the lower end of a short shaft 96 journaled in a collar 97 upon the lower end of a bracket 98. 99 indicates a worm-gear keyed upon the upper end of

said shaft 96, meshing with which is a worm 100 keyed upon the sleeve 25.

Loosely mounted on the shaft 78 between collars 101 are two collars 102-103, the bearing of the collar 102 upon the shaft 78 being in the form of a slot, as shown in Fig. 9. Rising diagonally from the collar 102 is an arm 104, the upper end of which is pivotally connected with a slideable plate 105, connected with which plate, through suitable slots in the lower end of said carriage 82, are slides 106 on the outside surface of said carriage, the upper ends of which are beveled to correspond to the beveled edges of the plate 71. Extending transversely from one face of said arm 104 is a stud or pin 107. Extending from the rear face of the collar 103 is an arm 108 provided with a slot 109 in its outer end adapted to embrace the pin 107.

Depending from the collar 103 is an arm 110, to the lower end of which is pivotally connected a link 111 whose forward end is pivotally connected to an arm 112 which is loosely mounted on the shaft or spindle 86.

113 indicates a link pivoted at its rear end to the arm 112 intermediate of its ends, and connected at its front end to a closed yoke 114 which embraces loosely the shaft 89.

115 indicates a cam disk provided with an annular cam groove 116 in which works a stud or roller 117 which is carried by the yoke 114.

118 indicates a shaft provided with a plurality of pulleys 119 keyed thereon, said shaft being journaled in the upper ends of pivoted arms 120 at the sides of the machine.

121 indicates a shaft provided with a plurality of pulleys 122 keyed thereon, said shaft 121 being journaled in the upper ends of standards 123.

124 indicates a table supporting bent strips 125.

126 indicates belts connecting pulleys 119 and 122 and extending along the strips 125.

127-128 indicate sprocket-wheels keyed upon the shafts 121-118, respectively, connected by a sprocket-chain 129 also extending along one of the strips 125. 130 indicates a sprocket-wheel loosely mounted upon the shaft 78, over which sprocket-wheel said chain runs. Connected with said sprocket-wheel 130 is a ratchet-wheel 131. Depending from the collar 80 is an arm 132, to the rear end of which is pivotally attached a pawl 133 adapted to contact the ratchet-wheel 131, and adapted to cause rotation of such ratchet-wheel and consequently of the sprocket-wheel 130 when the carriage 82 is moved from vertical position to inclined position as hereinafter described.

134 indicates a water-pipe adapted to be connected with any suitable head of cold water. 135 indicates a flexible hose con-

nected with said pipe 134 and with a pipe 136 held in position in the carriage 82 and provided with suitable openings in its rear face whereby when the water is fed to said pipe 136 a plurality of jets of water are adapted to be sprayed upon the inner surface of said carriage, openings 137 being provided through the wall of said carriage for the purpose of permitting the water 10 to get to the stereotype plate as hereinafter described. 138 indicates a valve in the lower end of said pipe 136 adapted to be opened by moving in a counter-clockwise direction an arm 139 connected therewith, which arm 15 extends through a suitable slot in the wall of the carriage 82.

140 indicates a water-pipe rising from the pipe 134 at one side of the carriage 82, to which is attached a curved pipe 141 with 20 a valve 142 interposed, said valve being adapted to be opened by the movement of an arm 143 in a clockwise direction in Figs. 1, 3 and 6. Said pipe 141 is provided with suitable openings in its lower rear side whereby when water is fed to said pipe a plurality of jets of water are adapted to be forced in a rearward and downward direction.

The mechanism is so arranged that when 30 the plate is released from the drum 20 and slides out therefrom, the carriage 82 is in its inclined position, as shown in Fig. 1, with the stops 106 in their uppermost position relative to the carriage. The plate therefore 35 slides out of the drum onto the carriage, the leading edge of the plate contacting the arm 139 and moving it downward, opening the valve 138 and causing a plurality of streams of cold water to play upon the interior surface of the carriage and through the openings 137 therein upon the inner surface of the plate 71, the leading edge of the plate coming later in contact with the stops 106 by which it is held securely in position. 40 As is readily understood, the shaft 89 and disk 115 are rotated in the direction indicated by the arrow in Fig. 3, through the medium of the short shaft 96 and its connected parts, during the time that the drum 45 is being rotated. After the plate 71 has slid out of the drum, the lever 47 is depressed a second time as hereinabove set forth, setting in operation again the drum and the shaft 89.

50 The arrangement is such that shortly after the plate 71 is moved to its position on the carriage and the shaft 89 is set to rotating, the cam groove 92 forces the pin 93 and links 87 and 84 to the right in Fig. 4, moving the arm 83 to the right and raising the carriage 82, bringing the upper end of the plate 71 thereon into contact with the arm 143 and opening the valve 142 causing a plurality of streams of cold water to be forced 55 onto the plate and the carriage from the

curved pipe 141. At the same time, the cam groove 116 forces the pin 117 and the links 113 and 111 to the right in Fig. 4 in unison with the movement of the pin 93 and the links 87 and 84 to the right. At 70 just about the time that the carriage reaches its vertical position, however, the cam groove 116 moves the pin 117 faster than the movement of the pin 93, as shown diagrammatically in Fig. 8, the links 113 75 and 111 therefore being given a movement relative to that of the links 87 and 84. That is to say, the collar 103 is given a slight rotation in a counter-clockwise direction relative to the collar 79, and the arrangement 80 of the parts is such that this happens when the arm 108 is moving downward and when the slot in the collar 102 is in a substantially vertical position. The result is that as the arm 108 continues to move downward and 85 the arm 110 continues to move to the right in Fig. 6, the collar 102 is lowered relative to the shaft 78, drawing downward the plate 105 and the stops 106, depositing the plate 71 standing on end upon the belts 126. 90

Shortly after the plate is deposited on the belts 126, the cam grooves 92 and 116 cause the carriage to descend and the stops 106 to rise again relative to the carriage, ready 95 to receive another plate from the drum 21 as just described. As the carriage moves away from the plate 71, it will be understood that the arm 139 is free to rise, thus shutting off the flow of water from the pipe 136 until the valve 138 is again opened 100 by the succeeding plate. As the carriage descends, the collar 80 is of course turned in a direction to actuate the sprocket-wheel 130 through the medium of the pawl 133 and ratchet-wheel 131, moving the upper portions 105 of the belts 126 to the left in Figs. 3 and 4, moving the plate 71 to the left out of the way of the plates to be thereafter delivered to the belts. As the plate 71 is moved to the left, it passes under the end 110 of the arm 143, whereupon said arm is free to move to close the valve 142, thus shutting off the flow of water from the pipe 144 until the valve is again opened by the next 115 succeeding plate.

It will be understood that some time after the carriage 82 is lowered into alinement with the drum and before the carriage begins again to ascend, the drum will have 120 been rotated into position to bring the roller 57 into contact with the cam 58, throwing out of engagement the clutch members 36 and 37 and stopping the rotation of the sleeve 25^a and its driven parts. In case a 125 number of plates are to be finished in succession, the second plate will ordinarily be placed in position in the drum before the lever 47 is depressed the second time to cool and deliver the first plate, thus one plate 130 being finished and another being cooled and

- delivered at the same time. I have indicated in the drawings in dotted lines a number of plates in position on the belts 126, the same being numbered 71^a.
5. What I claim as my invention and desire to secure by Letters Patent is,—
1. In a stereotype plate finishing machine, the combination with a frame and a drum mounted thereon with one end higher than the other, of a table pivotally mounted on said frame in front of said drum and adapted to be turned either into a horizontal position or into inclined position in alinement with said drum.
  15. 2. In a stereotype plate finishing machine, the combination with a frame, and a drum mounted thereon with one end higher than the other, of a table mounted on said frame in front of said drum on a pivot intermediate of the ends of said table and adapted to be turned either into a horizontal position or into inclined position in alinement with said drum, and stops adapted to limit the movement of said table.
  25. 3. In a stereotype plate finishing machine, the combination with a frame, and a drum mounted thereon with one end higher than the other, of a table pivotally mounted on said frame in front of said drum and adapted to be turned either into a horizontal position or into inclined position in alinement with said drum, said table being curved at one end to conform to the curvature of a stereotype plate and being so positioned that when said table is turned into inclined position with a plate thereon said plate is adapted to slide into position in said drum.
  35. 4. In a stereotype plate finishing machine, the combination with a frame and a drum mounted thereon with one end higher than the other, of a table pivotally mounted on said frame in front of said drum and adapted to be turned either into a horizontal position or into inclined position in alinement with said drum, and guiding means on said table whereby when said table is turned into inclined position with a plate thereon said plate will automatically slide into position in said drum.
  45. 5. In a stereotype plate finishing machine, the combination with a frame and a drum mounted thereon with one end higher than the other, of a table pivotally mounted on said frame in front of said drum and adapted to be turned either into a horizontal position or into inclined position in alinement with said drum, guiding means on said table whereby when said table is turned into inclined position with a plate thereon said plate will automatically slide into position in said drum.
  55. 6. In a stereotype plate finishing machine, the combination with a frame and a drum mounted thereon with one end higher than the other, of a table pivotally mounted on said frame in front of said drum and adapted to be turned either into a horizontal position or into inclined position in alinement with said drum, guiding means on said table whereby when said table is turned into inclined position with a plate thereon said plate will automatically slide into position in said drum, and a stop adapted to limit the movement of said plate into said drum.
  60. 65. 7. In a stereotype plate finishing machine, the combination with a frame and a drum mounted thereon with one end higher than the other, of a table pivotally mounted on said frame in front of said drum and adapted to be turned either into a horizontal position or into inclined position in alinement with said drum, guiding means on said table whereby when said table is turned into inclined position with a plate thereon said plate will automatically slide into position in said drum, and a stop on said table adapted to permit said plate to slide into position in said drum but adapted to contact with an appropriately-positioned lug on the tail of said stereotype plate to limit the movement of said plate into said drum.
  70. 8. In a stereotype plate finishing machine, the combination with a frame, and a drum mounted thereon with one end higher than the other, of a table pivotally mounted on said frame in front of said drum and adapted to be turned either into a horizontal position or into inclined position in alinement with said drum, plate supporting ribs carried by said drum, and guiding means on said table whereby when said table is turned into inclined position with a plate thereon said plate will automatically slide into position upon said ribs.
  80. 9. In a stereotype plate finishing machine, the combination with a frame, a drum mounted thereon with one end higher than the other and adapted to hold a stereotype plate therein while it is being finished, and means for releasing said plate from said drum leaving it free to slide therefrom, of a carriage adapted to receive said stereotype plate thereon when it moves out of said drum, and means for swinging said carriage into vertical position to deliver said plate.
  85. 10. In a stereotype plate finishing machine, the combination of a drum adapted to hold a stereotype plate therein while it is being finished, a carriage adapted to receive said plate thereon from said drum, and means for swinging said carriage into vertical position to deliver said plate.
  90. 11. In a stereotype plate finishing machine, the combination with a drum adapted to hold a stereotype plate therein while it is being finished, said plate being adapted to be moved automatically out of said drum when finished, of a carriage adapted to receive said stereotype plate thereon when it is moved out of said drum, means for swinging said carriage into vertical position to deliver said plate, and means for cooling said plate while it is in contact with said carriage.
  100. 12. In a stereotype plate finishing machine, the combination with a drum adapted to hold a stereotype plate therein while it is being finished and adapted to automatically discharge said plate when finished, of a carriage adapted to receive said stereotype plate thereon when it is moved out of said drum, means for swinging said carriage into vertical position to deliver said plate, and means for cooling said plate while it is in contact with said carriage.
  105. 13. In a stereotype plate finishing machine, the combination with a drum adapted to hold a stereotype plate therein while it is being finished, said plate being adapted to be moved automatically out of said drum when finished, of a carriage adapted to receive said stereotype plate thereon when it is moved out of said drum, means for swinging said carriage into vertical position to deliver said plate, and means for cooling said plate while it is in contact with said carriage.
  110. 14. In a stereotype plate finishing machine, the combination with a drum adapted to hold a stereotype plate therein while it is being finished, said plate being adapted to be moved automatically out of said drum when finished, of a carriage adapted to receive said stereotype plate thereon when it is moved out of said drum, means for swinging said carriage into vertical position to deliver said plate, and means for cooling said plate while it is in contact with said carriage.
  115. 15. In a stereotype plate finishing machine, the combination with a drum adapted to hold a stereotype plate therein while it is being finished, said plate being adapted to be moved automatically out of said drum when finished, of a carriage adapted to receive said stereotype plate thereon when it is moved out of said drum, means for swinging said carriage into vertical position to deliver said plate, and means for cooling said plate while it is in contact with said carriage.
  120. 16. In a stereotype plate finishing machine, the combination with a drum adapted to hold a stereotype plate therein while it is being finished and adapted to automatically discharge said plate when finished, of a carriage adapted to receive said stereotype plate thereon when it is moved out of said drum, means for swinging said carriage into vertical position to deliver said plate, and means for cooling said plate while it is in contact with said carriage.
  125. 17. In a stereotype plate finishing machine, the combination with a drum adapted to hold a stereotype plate therein while it is being finished and adapted to automatically discharge said plate when finished, of a carriage adapted to receive said stereotype plate thereon when it is moved out of said drum, means for swinging said carriage into vertical position to deliver said plate, and means for cooling said plate while it is in contact with said carriage.
  130. 18. In a stereotype plate finishing machine, the combination with a drum adapted to hold a stereotype plate therein while it is being finished and adapted to automatically discharge said plate when finished, of a carriage adapted to receive said stereotype plate thereon when it is moved out of said drum, means for swinging said carriage into vertical position to deliver said plate, and means for cooling said plate while it is in contact with said carriage.

- vertical position to deliver said plate, and means for spraying a cooling fluid upon said plate while it is in contact with said carriage.

5. 12. In a stereotype plate finishing machine, the combination with a drum adapted to hold a stereotype plate therein while it is being finished and adapted to automatically discharge said plate when finished, of a carriage adapted to receive said stereotype plate thereon when it is moved out of said drum, means for swinging said carriage into vertical position to deliver said plate, a perforated pipe carried by said carriage and movable therewith connected with a source of suitable cooling fluid, and automatically-operated means for admitting said cooling fluid to said pipe whereby it is distributed over said plate while it is in contact with said carriage.

10. 13. In a stereotype plate finishing machine, the combination with a drum adapted to hold a stereotype plate therein while it is being finished and adapted to automatically discharge said plate when finished, of a carriage adapted to receive said stereotype plate thereon when it is moved out of said drum, means for swinging said carriage into vertical position, belts to which said plate is adapted to be automatically delivered standing on end before said carriage is swung out of vertical position.

15. 14. In a stereotype plate finishing machine, the combination of a drum adapted to hold a stereotype plate therein while it is being finished, a carriage adapted to receive said plate thereon from said drum, and automatically-operated means for swinging said carriage into vertical position to deliver said plate and then for returning said carriage into position to receive another plate from said drum.

20. 15. In a stereotype plate finishing machine, the combination with a drum adapted to hold a stereotype plate therein while it is being finished and adapted to automatically discharge the plate when finished, of a carriage adapted to receive said stereotype plate thereon when it is moved out of said drum, means for swinging said carriage into vertical position, belts to which said plate is adapted to be automatically delivered standing on end before said carriage is swung out of vertical position, and means for moving said belts to carry said plate away.

25. 16. In a stereotype plate finishing machine, the combination with a drum adapted to hold a stereotype plate therein while it is being finished and adapted to automatically discharge the plate when finished, of a carriage adapted to receive said stereotype plate thereon when it is moved out of said drum, means for supporting said plate in position on said carriage, a cam adapted by its rotation to automatically swing the carriage into vertical position when the plate has been slid into position on said carriage, a second cam adapted by its rotation to release said plate from the carriage when said carriage and plate have been raised, and means for driving said cams.

30. 17. In a stereotype plate finishing machine, the combination with a drum adapted to hold a stereotype plate therein while it is being finished, and adapted to automatically discharge the plate when finished, of a carriage adapted to receive said stereotype plate thereon when it is moved out of said drum, a cam adapted by its rotation to automatically swing the carriage into vertical position to deliver the plate when it has been slid into position on said carriage, and pawl and ratchet mechanism actuated by the movement of said carriage in one direction to drive said sprocket-chain.

35. 18. In a stereotype plate finishing machine, the combination with a drum adapted to hold a stereotype plate therein while it is being finished, and adapted to automatically discharge the plate when finished, of a carriage adapted to receive said stereotype plate thereon when it is moved out of said drum, a cam adapted by its rotation to automatically swing the carriage into vertical position to deliver the plate when it has been slid into position on said carriage, and means for driving said cam.

40. 19. In a stereotype plate finishing machine, the combination with a drum adapted to hold a stereotype plate while it is being finished and adapted to automatically discharge the plate when finished, of a carriage adapted to receive said stereotype plate thereon when it is moved out of said drum, means for supporting said plate in position on said carriage, a cam adapted by its rotation to automatically swing the carriage into vertical position when the plate has been slid into position on said carriage, a second cam adapted by its rotation to release said plate from the carriage when said carriage and plate have been raised, and means for driving said cams.

45. 20. In a stereotype plate finishing machine, the combination with a drum adapted to hold a stereotype plate while it is being finished, said plate being adapted to be moved automatically out of said drum when finished, of a carriage adapted to receive said stereotype plate thereon when it is moved out of said drum, means for supporting said plate in position on said carriage, a cam adapted by its rotation to automatically swing the carriage into vertical position when the plate has been slid into position on said carriage, a second cam adapted by its rotation to release said plate from said carriage when the carriage and plate have been raised.

50. 21. In a stereotype plate finishing machine, the combination with a drum adapted to hold a stereotype plate while it is being finished, said plate being adapted to be moved automatically out of said drum when finished, of a carriage adapted to receive said stereotype plate thereon when it is moved out of said drum, means for supporting said plate in position on said carriage, a cam adapted by its rotation to automatically swing the carriage into vertical position when the plate has been slid into position on said carriage, a second cam adapted by its rotation to release said plate from said carriage when the carriage and plate have been raised.

55. 22. In a stereotype plate finishing machine, the combination with a drum adapted to hold a stereotype plate while it is being finished, said plate being adapted to be moved automatically out of said drum when finished, of a carriage adapted to receive said stereotype plate thereon when it is moved out of said drum, means for supporting said plate in position on said carriage, a cam adapted by its rotation to automatically swing the carriage into vertical position when the plate has been slid into position on said carriage, a second cam adapted by its rotation to release said plate from said carriage when the carriage and plate have been raised.

60. 23. In a stereotype plate finishing machine, the combination with a drum adapted to hold a stereotype plate while it is being finished, said plate being adapted to be moved automatically out of said drum when finished, of a carriage adapted to receive said stereotype plate thereon when it is moved out of said drum, means for supporting said plate in position on said carriage, a cam adapted by its rotation to automatically swing the carriage into vertical position when the plate has been slid into position on said carriage, a second cam adapted by its rotation to release said plate from said carriage when the carriage and plate have been raised.

65. 24. In a stereotype plate finishing machine, the combination with a drum adapted to hold a stereotype plate while it is being finished, said plate being adapted to be moved automatically out of said drum when finished, of a carriage adapted to receive said stereotype plate thereon when it is moved out of said drum, means for supporting said plate in position on said carriage, a cam adapted by its rotation to automatically swing the carriage into vertical position when the plate has been slid into position on said carriage, a second cam adapted by its rotation to release said plate from said carriage when the carriage and plate have been raised.

raised, belts upon which said plate is adapted to be lowered standing on end when it is released from said carriage, means for driving said cams, and means actuated by the downward movement of said carriage for moving said belts to carry away said plate.

21. The combination of a carriage adapted to be swung about a fixed axis, a cam-operated reciprocatory link adapted for swinging said carriage up and down, a slidable stop carried by said carriage, and a second cam-operated reciprocatory link connected with said stop adapted to move a part of the time in unison with said first-mentioned link but adapted to move farther than said first-mentioned link in order to lower and raise said stop at suitable times relative to said carriage.

22. The combination with a shaft, an arm rising therefrom, a carriage secured to said arm, and a reciprocatory link adapted for rotating said shaft to swing said carriage

up and down, of a collar mounted on said shaft, the bearing of which collar is in the form of a slot, an arm rising from said collar, a stop slidably mounted on said carriage and pivotally connected with said second-named arm, an arm revolvably mounted on said shaft provided with a longitudinally-extending slot, a pin extending transversely from said second-named arm and adapted to work freely in the slot located in said third-named arm, and a second reciprocatory link adapted to move a part of the time in unison with said first-mentioned link but adapted to move farther than said first-mentioned link, thus causing said second-named arm and said stop to be lowered relative to said carriage.

SAMUEL G. GOSS.
